(57) **CLAIM**

The ornamental design for a networking device as shown and described.

DESCRIPTION

FIG. 1 is a top perspective view of a networking device, showing our new design;

FIG. 2 is a bottom perspective view of the networking device shown in FIG. 1;

FIG. 3 is a front view of the networking device shown in FIG. 1;

FIG. 4 is a rear view of the networking device shown in FIG. 1;

FIG. 5 is a left side view of the networking device shown in FIG. 1;

FIG. 6 is a right side view of the networking device shown in FIG. 1;

FIG. 7 is a top view of the networking device shown in FIG. 1; and,

FIG. 8 is a bottom view of the networking device shown in FIG. 1.

The broken lines shown in the FIGURES depict portions of the networking device that form no part of the claimed design.
